MERCHANDISE DISPLAY STAND

Robert A. Wellington, Warren, Ohio

Application August 19, 1957, Serial No. 47,437

Term of patent 3½ years

(Cl. D80—9)

Figure 1 is a perspective view of a merchandise display stand, showing my new design, the other side being substantially the same; and

I claim:
The ornamental design for a merchandise display stand, substantially as shown and described.
